(57) **CLAIM**

The ornamental design for a power control device with a substantially square footprint, as shown and described.

DESCRIPTION

FIG. 1 is a full isometric view of the square modular dimmer speed control device having an annular light transmissive region or annular marking, the speed control device being shown as it comes from the factory on its mounting plate, the plate and integral hardware behind it being shown in environmental lines;

FIG. 2 is the same isometric view of the modular dimmer speed control device depicted in FIG. 1 as seen extending through a central square shaped opening of a wall plate cover, the wall plate cover being shown in environmental lines; FIG. 3 is a front elevation view thereof (Note: no back elevation view is shown because nothing is claimed about that side of the invention);

FIG. 4 is a right side elevation view thereof;

FIG. 5 is a right side elevation view thereof;

FIG. 6 is a top plan view thereof;

FIG. 7 is a bottom plan view thereof;

FIG. 8 is another alternate embodiment of the square modular dimmer speed control device depicted in FIGS. 1-7, the control device including a center light transmissive region or marking surrounded by an annular light transmissive region or marking;

FIG. 9 is a full isometric view of a square modular dimmer speed control device having an annular light transmissive region or annular marking, the speed control device being shown as it comes from the factory on its mounting plate, the plate and integral hardware behind it being shown in environmental lines;

FIG. 10 is the same isometric view of the control device depicted in FIG. 9 as seen extending through a central square shaped opening of a wall plate cover, the wall plate cover being shown in environmental lines;

FIG. 11 is a front elevation view of the modular dimmer speed control device depicted in FIG. 9 (Note: no back elevation view is shown because nothing is claimed about that side of the invention);

FIG. 12 is a right side elevation view of the control device depicted in FIG. 9;

FIG. 13 is a left side elevation view of the control device depicted in FIG. 9; FIG. 14 is a top plan view of the control device depicted in FIG. 9;

FIG. 15 is a bottom plan view of the control device depicted in FIG. 9; and,

FIG. 16 is another alternate embodiment of the square modular dimmer speed control device depicted in FIGS. 9-15, the control device including a center light transmissive region or marking surrounded by an annular light transmissive region or marking.

The broken line showing of the environment is for illustrative purposes only and forms no part of the claimed design.

1 Claim, 10 Drawing Sheets
